UNITED STATES PATENT OFFICE.

STANLEY D. ROBINSON, OF HAMILTON, ONTARIO, CANADA, ASSIGNOR TO D. MOORE COMPANY, LIMITED, OF HAMILTON, CANADA.

DESIGN FOR A FIREPLACE FRONT.

Application filed October 3, 1925. Serial No. 15,013. Term of patent 7 years.

To all whom it may concern:

Be it known that I, STANLEY D. ROBINSON, a subject of the King of Great Britain, residing at Hamilton, in the county of Wentworth and Province of Ontario, Canada, have invented a new, original, and ornamental Design for Fireplace Front, of which the following is a specification, reference being had to the accompanying drawing, forming part thereof.

I claim:

The ornamental design for a fireplace front, as shown.

STANLEY D. ROBINSON.
